UNITED STATES PATENT OFFICE.

FREDERICK W. HEDGELAND, OF CHICAGO, ILLINOIS.

Mounting for Piano-Keys.

SPECIFICATION forming part of Letters Patent No. 669,729, dated March 12, 1901.

Application filed November 17, 1900. Serial No. 36,838. (No model.)

To all whom it may concern:
Be it known that I, FREDERICK W. HEDGELAND, a citizen of the United States, residing at Chicago, in the county of Cook and State 5 of Illinois, have invented certain new and useful Improvements in Mountings for Piano-Keys; and I do hereby declare the following to be a full, clear, and exact description of the invention, such as will enable others 10 skilled in the art to which it appertains to make and use the same.

This invention relates to a mounting for pianoforte-keys and like musical instruments, and has for its object to provide an 15 arrangement of this character that will prevent the free action or movement of the keys from being affected by atmospheric changes. It is well known that when the atmosphere is charged with excessive moisture, as in 20 damp weather, the keys have a tendency to stick, and a free action is thus prevented, often causing great annoyance and temporarily disabling the instrument. Under the ordinary arrangement when the wooden key- 25 lever absorbs moisture the walls inclosing the pins swell and exert a side pressure on the pins, which are usually oval in cross-section, and cause the keys to stick or cramp.

In the accompanying drawings, Figure 1 is 30 a broken-away side elevation of a key, the supporting base-rails being shown in section. Fig. 2 is a vertical transverse section on line 2, Fig. 1, looking in the direction indicated by the arrow. Fig. 3 is a view in perspective 35 of a bearing-sleeve. Fig. 4 is a similar view looking at the opposite end of the sleeve, and Fig. 5 is a plan section of the same.

A represents a piano-key of the usual 40 form; B, the center rail of the supporting-frame, in which the key fulcrum-pin *a* is mounted; C, the front rail, in which the movement-pin *D* is fixed, and *b* the usual flexible cushion-seat, on which the front end of the key-lever strikes.

45 The key is provided with a chamber or recess *6*, starting in from the under side and stopping short of the top, as more particularly shown in Fig. 2. The movement or guide pin *D* projects into this chamber and 50 is surrounded by a sleeve *7*, seated in said chamber and rigidly secured in place by screws or other suitable fastening devices,

inserted through holes *8* in the stop-flange *9*, forming a part of the sleeve. The sleeve is elongated, as shown, and is provided in one 55 end with vertical companion slots *10*, across which the integral spurs *11* extend, as shown in Fig. 3. The other end of the sleeve is provided with companion slots *12*, Fig. 4.

The interior sides of the sleeve are provided with a flexible or soft lining *13*, usually of felt or other suitable material. This lining is usually in the form of strips of suitable length and width, the respective ends of which are first inserted through slots *12* from 60 the outside and then carried along and drawn out through the spur-guarded slots *11*, the spurs yielding for the passage of the lining, the terminal ends of which may be secured together in any suitable manner, as shown 65 at *14*, Fig. 5. As the lining is rove through it is drawn taut on the bridge-piece *15*, between slots *12*, and is engaged by the spurs *11*, causing the lining to adhere closely to the inner sides of the sleeve, as clearly illustrated in Fig. 5. By this means the lining is secured in place without the use of glue or adhesive composition to harden the surfaces having contact with the bearing-surfaces of the movement-pin. The lining has 70 contact with the opposite sides of the key-pin, Fig. 2, and provides a cushion-bearing, which always retains the key in its proper position, provides for a free up-and-down movement 75 of the same, and prevents the keys from crowding laterally against each other. This sleeve arrangement not only provides a uniform bearing-guide for the movement-pin, but prevents an inward pressure on the same when the key-lever expands, as it will naturally enlarge in the direction of the least 80 resistance, which is outwardly from both sides.

Under the ordinary arrangement the key is provided with a chamber or mortise-recess lined with some suitable soft fabric, which is 85 secured to the walls of the chamber by an adhesive composition, usually glue, a fair proportion of which is absorbed by the fabric and when set presents a hard bearing-surface for the contact of the movement-pin even under normal conditions and which is aggravated when the key-lever is expanded from natural causes, as the lateral expansion will be equal 90 in both directions and will necessarily have 100

a tendency to pinch and bind the keys just sufficiently to interfere with a free action thereof.

Having thus described my invention, what I claim as new, and desire to secure by Letters Patent, is—

1. The combination with a piano-key, of a sleeve, inserted therein and provided with slots through which a sort of flexible lining 10 may be drawn, and means for retaining said lining in place, substantially as described.

2. The combination with a piano-key, of a sleeve, seated therein, and provided at opposite points with slots, a felt lining drawn 15 through the slots, and a number of spurs, traversing one or more of said slots and engaging said lining, substantially as described.

3. The combination with the keys of a piano or like musical instrument, of a metallic 20 sleeve, recessed in the under side thereof and provided with a number of slots, a cushion-lining, inserted in the sleeve by being drawn through the slots, the spurs, extending across one or more of said slots and engaging said

lining, and means for retaining the sleeve in place, substantially as described.

4. The combination with a piano-key, of an elongated sleeve, recessed therein and provided in opposite ends with a number of slots, a felt lining, inserted in the sleeve by being drawn through the slots therein, and means, other than an adhesive composition, for securing said lining in place, substantially as described.

5. The combination with a piano-key, of a sleeve, recessed in the under side thereof and provided with a number of slots, the spurs, guarding one or more of said slots, a lining, inserted in the sleeve and retained therein by said spurs, the guide-pin, and the rail, in which the same is mounted, substantially as described.

In testimony whereof I affix my signature in presence of two witnesses.

FREDERICK W. HEDGELAND.
